UNITED STATES PATENT OFFICE.

CHARLES B. SHAW, OF MALDEN, MASSACHUSETTS.

CLOTH-MEASURING MACHINE.

SPECIFICATION forming part of Letters Patent No. 276,722, dated May 1, 1883.

Application filed June 16, 1882. (No model.)

To all whom it may concern:

Be it known that I, CHARLES B. SHAW, of Malden, county of Middlesex, State of Massachusetts, have invented an Improvement in Cloth-Measuring Machines, of which the following description, in connection with the accompanying drawings, is a specification.

My invention has for its object the production of an efficient machine for measuring cloth, and also, if desired, removing from it its selvage edges.

In manufacturing establishments using large quantities of cloth it is very desirable to inspect the cloth carefully and remeasure the same before given into the hands of the cutters, and while the selvage edges are torn off. To accomplish this object I have devised a machine containing a suspension-roller, over which the cloth is laid and led between feeding-rollers, which hold the cloth distended, so that it may be examined. From the feeding-rollers the cloth passes over a measuring-roller and between it and a pressure roller or rollers. I have provided the machine with selvage-tearing rollers, which, the ends of the selvage strips being started between them, act to tear the selvages from the cloth.

Figure 1 represents in a front side elevation a cloth-measuring machine embodying my invention; Fig. 2, a detail of the measuring devices, and Fig. 3 a vertical section of Fig. 1 on the dotted line *x x*.

The frame-work *A*, of suitable shape to hold the working parts, has at its rear side a yoke-frame, *B*, provided with uprights to serve as bearings for the journals of a suitable plate or board, *a*, which is extended through the center of the roll, especially if of double-width cloth, as shown at *C*. The outer end of the cloth, taken from the said roll and unfolded, is passed over the sustaining-roller *b* at the top of the machine, and led down in front of the rollers *c d*, under the tension-roller *e*, and then up over the measuring-roller *f*. Each roller *c d f* has a portion of its surface covered, as at *g g²*, with an abrasive material—such as sand or emery or sand-paper—the said surface being sufficiently rough to cause the cloth or material to be kept pressed in contact with it by other yielding rollers to be described, to travel at the same speed as do the rollers *c d e*,

The selvage of the cloth, supposing double-width woolen cloth is to be examined and measured, is torn off for a yard or more at each side of the cloth and led upward over the surfaces *g* of the selvage-roller *c* and between said surfaces and the rollers *h*, having preferably elastic surfaces and having their journals held in spring-arms *h²*, attached to the cross-beam *h³*. The roller *c* and small rollers *h* constitute the selvage tearing or removing devices. In case the cloth was of single width the surface *g²*, with suitable rollers opposed to it, would co-operate with one selvage, two single-width pieces of cloth being simultaneously examined and measured and having their selvages removed. The main part of the cloth does not touch the roller *c*, but extends from the sustaining-roller over the edge of the cloth-support *i*, made as a beam, more or less inclined, the upper edge of which is so located with relation to the feeding-rollers *d* as to prevent the cloth falling back on the top of the said roller.

The roller *d*, composing one of the feeding-rollers, has in front of it the small rollers *m*, having preferably elastic surfaces, and having their journals in heads *m²*, adjustably connected with the springs *m³*, which latter act to cause the said rollers *m* to keep the body of the cloth pressed against the rough surfaces *g* of the roller *d* to feed the cloth through the machine. The cloth will be drawn in one direction by rollers *d m*, and the selvages in the opposite direction by the rollers *c h*, which cause the selvages to be torn from the cloth. The selvage is shown at *o*, Fig. 3. The heads *m²* are made adjustable on their spring carrying arms or supports by screws *m⁴*, so that the axis of each roller *m* may be more or less inclined with relation to the axis of roller *d*, to thereby act to draw and stretch the cloth in the direction of its width, as operate the temple-rollers in looms.

Instead of supporting the journals of rollers *h m* in spring-arms, the heads holding the said journals might have shanks extended through guides, the said shanks being provided with springs in any usual manner. In other words, instead of supporting the rollers *h* and *m* in yielding manner in the exact manner herein shown, I may support them in a yielding man-

ner by any other well-known devices than the arms $h^2 m^3$.

The cross-piece n bears on the cloth below the feeding-roller d , forcing the cloth backward, so as to cause a greater length of cloth to bear against the rough surface g . This cross-piece n might be adjustable. The end pieces, 7, of the tension-roller c enter guideways formed between the frame and pieces of metal e^2 .

10 The main driving-belt p of the machine is passed about a pulley, p' , on shaft of roller c , and roller d is driven in a reverse direction by the crossed belt p^3 , extended over pulley p^2 on shaft of roller c and pulley p^4 on shaft of roller d . The shaft of roller d has a screw-pulley, p^5 , which receives belt p^6 , extended over pulley p^7 on the shaft of the measuring-roller f , the latter having at its other end a bevel-gear, f^2 , which engages a bevel-gear, f^3 , on a shaft, f^4 , having a worm, f^5 , that engages a worm-gear, f^6 , on a stud, f^7 , with which is connected a pointer, f^8 , to travel about the dial f^9 , numbered or figured to designate yards.

I do not desire to limit my invention to the exact devices shown and described for turning the pointer f^4 , (shown in Fig. 1 and partially in Fig. 2,) as instead of the said devices I may employ any usual counting mechanism commonly used in cloth-measuring machines.

30 The cloth is kept pressed against the rough surfaces of the measuring-roller by the pressure-rollers r on a rod, r^2 , held in arms r^3 , pivoted at r^4 on a rigid part of the frame-work. When the cloth is being passed over roller f the rod r^2 will be caught in the hook 12. The double-width cloth C is unfolded between the point where it leaves the roll of cloth and its arrival on the rest s at the rear of the roller b .

If the cloth be of single width, the holding-bar t will be employed. To apply a single-width web to the bar t the "bolt of cloth" will be held in place just below the bar, the outer end of the cloth will be passed up over the bar on one side and down on its other side, and thence under the bolt of cloth, and thence up above the roller b and down in the course

shown by cloth C . In this way it will be understood that a loop in the cloth itself, below the bar t , holds the web of cloth, which is gradually unrolled as the cloth is drawn by the feed-rollers $d m$. The yoke B is set so as to keep the roll of cloth C and the journals of the shaft or board holding it at right angles to the rollers $c d$.

I do not herein broadly claim the selvage-tearing apparatus of itself, as it will form the subject-matter of a future application for Letters Patent of the United States.

I claim—

1. The roll b , roller d , having a roughened surface, means to move it, and spring-pressed rollers m to hold the cloth against the roller d , as described, combined with the measuring-roller, means to move it, a dial and pointer, and intermediate mechanism operated by the said measuring-roller to actuate the pointer, all constructed and arranged substantially as described.

2. In a cloth-measuring machine, the rough-surfaced roller d and means to rotate it, combined with the yielding rollers $m m$ and means to support and adjust the same to place the axes of the said rollers m at an inclination to the axis of the roller d , whereby the rollers act to stretch the cloth in the direction of its width, substantially as described.

3. In a cloth-measuring machine, the combination of the following instrumentalities, viz: a cloth-measuring roller, f , means between it and the pointer to move the latter, feeding-rollers $d m$, selvage-tearing rollers $c h$, and cloth-sustaining roll b , and means to rotate the rollers $c d f$ positively, substantially as and for the purposes set forth.

In testimony whereof I have signed my name to this specification in the presence of two subscribing witnesses.

CHARLES B. SHAW.
